CONTROL FOR TWO-TEMPERATURE
REFRIGERATORS

Leslie B. M. Buchanan, Springfield, Mass., assignor to Westinghouse Electric & Manufacturing Company, East Pittsburgh, Pa., a corporation of Pennsylvania

Application October 22, 1936, Serial No. 106,976

14 Claims.

(Cl. 62—4)

My invention relates to refrigerating apparatus having relatively high and low temperature refrigerated cooling chambers and has for an object to provide improved apparatus of this character.

In two temperature refrigerating apparatus, separate evaporating elements are usually disposed in the high and low temperature chambers to maintain the chambers at different refrigerated temperatures. It has been suggested, heretofore, to control the cooling effect of the higher temperature evaporator by operating a fan in the warmer compartment for circulating air over the warmer evaporator in response to the temperature of the warmer compartment or evaporator. In accordance with my invention, such a system is utilized, and in addition preference is given to the colder compartment so that it will receive refrigeration when required, regardless of the heat load on the warmer evaporator.

In the aforementioned prior art devices, the fan was usually stopped with the condensing unit, or only was operated when the temperature of the warm compartment rose above a predetermined minimum. Such a system has several disadvantages. For example, the air in the warm compartment circulates very slowly when the fan is inactive with the result that some portions of the warmer compartment rise to an unsafe temperature. Furthermore, in certain types of two temperature systems, the warmer evaporator may operate below freezing and collect frost, thus reducing its effectiveness and also lowering the relative humidity in the warmer compartment in which it is desirable to maintain a fairly high relative humidity. Furthermore, a certain amount of the thermal storage capacity of the warmer evaporator may be lost.

In accordance with my invention, therefore, in normal operation preferably when the colder evaporator does not require refrigeration, I have devised various schemes for operating the fan after the condensing unit has shut down, preferably independently of the air temperature in the warmer compartment. For example, the fan may be operated after the condensing unit shuts down until a predetermined high temperature of the warmer evaporator is reached, or means may be employed for periodically stirring the air in the warmer compartment after the condensing unit has been shut down or the fan may run continuously regardless of the temperature of the warmer compartment or warmer evaporator

until the colder evaporator or compartment requires refrigeration.

Accordingly, it is a further object of my invention to effect forced circulation of air within the cooling chamber of a refrigerator during periods when the chamber is refrigerated.

A further object of my invention is to render the air translating means in one cooling chamber of a two chamber refrigerator inactive during periods when the other chamber calls for cooling.

A still further object of my invention is to effect circulation of air in the cooling chamber of a refrigerator for a period of time subsequent to terminating refrigeration of the evaporator therein.

Another object of the invention is to periodically effect circulation of air in the cooling chamber of a refrigerator.

These and other objects are effected by my invention as will be apparent from the following description and claims taken in connection with the accompanying drawing, forming a part of this application, in which:

Fig. 1 is a diagrammatic view of a refrigerating system arranged in accordance with my invention; and,

Figs. 2 and 3 are diagrammatic views showing second and third embodiments of the invention, respectively.

30

First embodiment (Fig. 1)

Reference will now be had to Fig. 1 in which I have shown a portion of a refrigerator cabinet 10 that includes relatively low and high temperature cooling compartments 11 and 12, respectively. Evaporator elements 13 and 14 abstract heat from the compartments 11 and 12 and receive refrigerant from a common condensing unit shown at 15. The condensing unit 15 includes a compressor 16 driven by a motor 17. The condensing unit 15 also includes a condenser 18 cooled in any suitable manner, such as, for example, by a motor driven fan 19.

Condensed refrigerant is conveyed from the condenser 18 to the evaporators 13 and 14 by a conduit 21 in which a conventional high side float valve 22 may be connected. The charge of refrigerant in the system is such that liquid refrigerant substantially fills both evaporators 13 and 14. The system operates on the compressor-condenser-expander cycle in which the compressor unit 16 withdraws vaporized refrigerant from the evaporators 13 and 14 through a conduit 23.

45

50

55

and compresses it to a relatively high pressure prior to its delivery to the condenser 18. The high pressure gas is cooled and condensed in the condenser 18 and then passes to the float valve 22. The pressure of the liquid refrigerant is reduced as it passes through the float valve 22 to the evaporators 13 and 14, wherein it is vaporized at low pressure for abstracting heat from the evaporators. This cycle continues repeatedly during the period that the compressor 16 operates.

The evaporator 13 may be employed for freezing fluids contained in trays 24 and for cooling the air in chamber 11 to a relatively low temperature. The evaporator 14 cools the air in the chamber 12 in which articles of food or other perishables may be stored. Suitable means such as, for example, a fan 25 driven by a motor 26 is employed for providing forced circulation of air in the chamber 12, whereby a relatively high rate of heat transfer between the air therein and the evaporator 14 is effected. During periods when the fan 25 is inactive, the rate of heat transfer is low so that refrigeration of the body of air in the chamber 12 is not effected to any material degree. Some limited cooling of the air is effected in the chamber 12 during inactive periods of the fan 25 due to thermally induced air currents but it is relatively small. Accordingly, effective refrigeration of the air in the compartment 12 accompanies operation of the fan 25 and, during inactive periods of the latter, effective refrigeration ceases. The evaporators 13 and 14 are cooled by refrigerant vaporized in each at a substantially equal pressure at any one time and cool the media in their respective compartments to different temperatures due to the difference in the rate of heat transfer between the respective evaporators and the media cooled thereby.

The temperature prevailing in the chamber 11 is controlled by a thermostat 27, shown by way of example, of the gas type and including a bellows 28 connected by a tube 29 to its temperature responsive bulb 31. As is well understood, the bulb of a gas type thermostat contains a suitable volatile fluid, the pressure of which is a function of its temperature. Accordingly, the bellows 28 expands and contracts as the temperature of the bulb 31 increases and decreases. Preferably, the bulb 31 responds directly to the temperature of the evaporator 13, being secured thereto as shown but it will be understood that it may be disposed otherwise in the chamber 11. A lever 32, pivoted at 33, is actuated by the bellows 28 and carries movable contacts 34 and 35 of a pair of switches 36 and 37, respectively, which switches include stationary contacts 38 and 39.

The temperature of the air in the chamber 12 is controlled by a bimetal thermostat 41, but which may be of any suitable type. It includes an expansible bimetallic member 42 that carries a movable contact 43, the latter being engageable with a stationary contact 44 for defining a switch structure 45. The controlling operation of the thermostats 27 and 41 will be referred to hereinafter.

The source of power for the various elements of my improved apparatus is represented by line conductors L₁ and L₂. The compressor motor 17 is connected directly to conductor L₂ and to the conductor L₁ by means of a conductor 46 controlled by the switch 36 of the thermostat 27.

Accordingly, when the temperature of the evap-

orator 13 rises to a predetermined value, the motor 17 is energized by the foregoing circuit and effects operation of the compressor unit 16.

A second circuit for energizing the motor 17 includes a conductor 47 extending from line conductor L₁ to the conductor 46 and controlled by the switch 45 of the thermostat 41. One terminal of the fan motor 26 is connected directly to the line conductor L₂ and the other terminal is connected to the conductor L₁ by means of a circuit including a conductor 48, controlled by the switch 37 of thermostat 27, and having a thermally actuated device 49 connected therein. The construction of the device 49 will now be described.

Included in the elements of the device 49 is a heat responsive member or disk 51, preferably of bimetal construction and defining the bridging member of a switch structure 52 having stationary contacts 53. The disk 51 is so constructed that it snaps into engagement with the contacts 53 when its temperature attains a predetermined high value and snaps to a circuit opening position out of engagement with the contacts 53 when its temperature is reduced to a predetermined value. The device 48 may be disposed in any suitable location, preferably, exterior of the cooling compartments 11 or 12. A relatively high resistance 54 is bridged across the contacts 53 and is shunted during periods when the disk 51 bridges the contacts 53, whereby the resistance 54 is deenergized. In the open position of the switch 52, the resistance 54 is energized for heating the disk 51.

Accordingly, when the switch 37 of thermostat 27 is closed, the resistance may be energized by a circuit including conductor L₁, closed switch 37, conductor 48, resistance 54, fan motor 26, and conductor L₂. The heated disk 51 snaps to a circuit closing position after a predetermined period of time and energizes the fan motor 26. Air is then circulated in the high temperature chamber 12. As the heater 54 is shunted by the disk 51, it cools and, after a predetermined period of time, the disk snaps to its open position and the fan 25 and motor 26 stop. The resistance 54 is then heated and this periodic cycling of the fan motor 26 continues as long as switch 37 is closed.

A second resistance 55 of relatively low value is disposed in heat transfer relation with the disk 51 and is connected in the conductor 47, controlled by the higher temperature thermostat 41. When the compressor motor 17 is energized by the thermostat 41, including conductor 47, the resistance 55 is connected in series with the motor 17 and, therefore, heats the disk 51 sufficiently to close the switch 52 and continuously energize the fan motor 26. Therefore, during periods when the high temperature thermostat 41 calls for cooling, the fan 25 is operated to continuously effect forced circulation in the chamber 12. Circulation of air in the chamber 12 for a period of time subsequent to the opening of thermostat 41 is effected, due to the heat stored in the disk 51 by the resistance 55.

The device 49, therefore, functions to effect forced circulation in the chamber 12 during periods when its thermostat 41 calls for cooling and to periodically effect air circulation during periods when both thermostats 41 and 27 are satisfied. During periods when the thermostat 27 calls for cooling, the fan motor 26 is deenergized, as the switch 37 is open.

Operation of Fig. 1

The position of the apparatus shown in Fig. 1 indicates that the temperatures prevailing in the chambers 11 and 12 are below values at which the thermostats 27 and 41 operate to effect circulation of refrigerant by the condensing unit 15, and, therefore, the thermostats 41 and 27 are satisfied. In this position, the fan 25 is periodically operated by the motor 26 to effect circulation of air in the chamber 12, due to the closure of switch 37 and the aforementioned cycling of the device 49. This operation keeps the air stirred in the chamber 12 whereby more even temperatures prevail throughout.

Due to heat load in the chambers 11 and 12, the pressure and temperature of both evaporators 13 and 14 rise. As the temperature of the evaporators rises to a predetermined value, the thermostat 27 operates to call for cooling, whereby the switches 36 and 37 close and open, respectively. The former effects operation of the condensing unit 15 as the motor 17 is energized as described heretofore. The fan 25 is rendered inactive to effect circulation of air in the compartment 12 due to the opening of switch 37.

The condensing unit 15 operates to translate refrigerant to the evaporators 13 and 14 for vaporization therein. Refrigeration of the chamber 11 is effected and, while the temperature of the evaporator 14 is depressed to a low value, refrigeration of the air in chamber 12 is not effected to any material degree due to the inactivity of the fan 25 and the resultant poor rate of heat transfer between the air and the evaporator 14. As the temperature of the evaporators 13 and 14 is depressed to the value at which the thermostat 27 is satisfied, the switch 36 is opened and the switch 37 is closed. Opening of switch 36 terminates operation of the condensing unit 15 and closing of the switch 37 conditions the circuit for operation of the fan motor 26.

Assume the temperature of the air in compartment 12 rises to the value at which the thermostat 41 calls for cooling, and that the thermostat 27 is satisfied. The switch 45 closes and energizes the compressor motor winding 17 through the circuit including conductor 47 and resistor 55. Circulation of refrigerant is initiated and continuous operation of the fan 25 is effected due to the heating of disk 51 by resistor 55, previously described. A high rate of heat transfer between the air in compartment 12 and the evaporator 14 is effected and cooling of the air in compartment 12 is obtained. At this time, the majority of refrigerant circulated is vaporized in the evaporator 14 due to the high heat load thereon.

During periods when both chambers 11 and 12 require cooling, the colder chamber 11 takes preference over the warmer chamber 12 as the switch 37 of the thermostat 27 is open for rendering the motor 26 and the fan 25 inactive. Refrigeration of chamber 11 is, therefore, effected in preference to chamber 12. After the chamber 11 is satisfied, control of the fan 25 and the condensing unit 15 is assumed by the thermostat 41, as is well understood.

Second embodiment (Fig. 2)

In the showing of the second embodiment of my invention (Fig. 2), I have, for the sake of clearness, deleted certain elements shown in Fig. 1 which are common to both embodiments, such as, the cabinet 10 and condensing unit 15, al-

though the motor 17 of the latter is shown. Elements shown which are common to both embodiments are indicated by the same numerals.

In the present embodiment, I show a thermostat 61 of the gas type having its bulb 62 disposed in heat transfer relation with the air in the chamber 12. The thermostat 61 actuates a movable contact 63 into engagement with stationary contacts 64 and 65 in response to a predetermined high temperature of the air in the compartment 12 and disengages the same in response to a predetermined low temperature of the air. The contacts 63, 64 and 65 define a switch structure 66. The movable contact 63 is connected to the line L₁ and the contact 64 is connected to a conductor 67 extending to one terminal of the fan motor 26 and controlled by the switch 37 of the thermostat 27. The contact 65 of the thermostat 61 is connected to a conductor 68 extending to one side of the winding 17 of the compressor motor and may include an inductive reactance 69, the purpose of which will be referred to hereinafter. The other terminals of the fan motor 26 and compressor motor 17 are connected to the line L₂, as shown.

A condensing unit (not shown) similar to that shown in Fig. 1 is controlled by the switch 36 of the thermostat 27 which switch is connected in a conductor 71 extending from line L₁ to the motor winding 17. A resistor 72 disposed in heat transfer relation with a thermo-responsive disc 73 is connected in the conductor 71 and is heated incidental to the energization of the motor winding 17 by the switch 36. The disc 73 is disposed in heat transfer relation with the evaporator 14 and operates to bridge stationary contacts 74 when cold and to open the same when relatively warm. The contacts 74 are connected in a conductor 75 forming part of a circuit extending from line L₁ to the fan motor 26.

When the evaporator 14 is below a predetermined temperature, for example, 35° F., the contacts 74 are bridged by the disc 73 and the fan motor 26 operates to circulate air within the chamber 12. The fan motor 26 may be deenergized by the disc 73 when it is actuated to open contacts 74 in response to an evaporator temperature above 35° F. The disc 73 may be actuated in an opening direction independently of the temperature of the evaporator 14 by means of the resistor 72 when energized.

Operation of Fig. 2

The position of the apparatus, as shown, indicates that both chambers 11 and 12 are below predetermined temperatures at which they demand cooling. Both thermostats 27 and 61 are satisfied and, therefore, their respective switches 36 and 66 are open. The condensing unit is idle at this time. In this position, the fan may or may not be operating, dependent upon whether temperature of the evaporator 14 is above or below 35° F. If it is below this value, the disc 73 bridges the contacts 74 and the fan 25 is operated by its motor 26; the latter being energized by a circuit including line L₁, conductor 75, motor 26 and line L₂. Accordingly, any ice formed on the evaporator 14 is melted and the air in the chamber 12 is circulated and cooled.

Assume the chamber 11 and evaporator 13 require cooling. The thermostat 27 operates to close switch 36 and to open switch 37. Opening of the latter is of no importance for the moment as switch 66 is open. Closure of switch 36, however, energizes the conductor 71, heater 72 and 75

- the compressor motor winding 17. Circulation of refrigerant by the condensing unit is initiated and the fan 25 is rendered inactive due to the opening of the contacts 74 by the heated disc 73.
- 5 Refrigeration of the chamber 11 is effected as described heretofore in connection with Fig. 1. As the temperature of the evaporator 13 is depressed to the desired value, the thermostat 21 moves to its satisfied position, whereby the 10 condensing unit is stopped and the heater 12 deenergized. As the temperature of the evaporator 14 is relatively low, the disc closes the contacts 74 and the fan 25 operates to circulate air for melting any accumulated frost on the 15 evaporator 14.
- Assume that the temperature of the air in the chamber 12 rises to the predetermined value at which the thermostat 61 moves to its switch closed position and that the thermostat 21 is 20 satisfied. The condensing unit is operated as its motor winding 17 is energized by a circuit including the line conductor L₁, movable contact 63, contact 65, reactance 69, conductor 68, winding 17 and line conductor L₂. The fan motor 26 25 is energized by a circuit including line conductor L₁, contacts 63 and 64, conductor 67, closed switch 37 of the thermostat 21, fan motor 26, and line conductor L₂. The air in the chamber 12 is, therefore, circulated and cooled as described, heretofore. As the temperature of the air in the chamber 12 is depressed to the desired value, the thermostat 61 is actuated to the position shown, whereby operation of the condensing unit is terminated. The fan 25 continues 30 operation, however, as its motor 26 continues to be energized due to the bridging of the contact 74 by the cold disc 73. The fan 25 stops operating when the temperature of the evaporator 14 and disc 73 rise to the assumed value of 35° F.
- 40 In the event of a demand for cooling from both compartments, the condensing unit will be operated by the preferred thermostat 21 in the manner described heretofore so that refrigeration of the cold compartment 11 is effected 45 and the fan 25 is inactive. At this time, the motor winding 17 is connected to the line conductor L₁ through parallel circuits, one of which includes the heater or resistance 12 and the other of which includes the reactance 69. Accordingly, 50 current flows in the conductor 71 and resistor 72 due to the voltage drop across the reactance 69, so that the fan 25 is rendered inactive by the heated disc 73 as described. When the thermostat 21 becomes satisfied, control of the 55 condensing unit 15 and fan 25 is assumed by the thermostat 61.

Third embodiment (Fig. 3)

In the third embodiment of my invention as shown in Fig. 3, certain parts shown in Fig. 1 are removed for the sake of clearness and elements appearing in the present embodiment which are common to the others carry like numerals. The fan motor 26, in this embodiment, is controlled solely by the switch 37 of the preferred low temperature thermostat 21 so that it is inactive when the latter calls for cooling of the chamber 11 and is active at all other times. One terminal of the motor 26 is connected to the line conductor L₁ and the other to a conductor 77 leading to the line conductor L₂ and controlled by the switch 37.

The winding of the compressor motor 17 has one terminal connected to line conductor L₂ directly and the other to a conductor 78. The

latter conductor 78 may be connected to the line conductor L₁ by the switch 36 or by a thermally actuated switch 79. The latter moves, in response to a predetermined high temperature of the air in chamber 12, to its circuit closed position and, in response to a predetermined low temperature of said air, to its circuit open position.

Operation of Fig. 3

As shown in Fig. 3, the thermostats 21 and 79 are satisfied so that the condensing unit not shown is not operating. The fan 25 is operating to circulate air in the chamber 12 and to remove frost from the evaporator 14. As the thermostat 21 calls for cooling, the fan is rendered inactive by the opening of the switch 37 and the winding of the compressor motor 17 is energized by the closure of switch 36. Accordingly, refrigerant is circulated for vaporization in the evaporators 13 and 14 by the condensing unit. When the temperature of the evaporator 13 is depressed to the desired value, the thermostat 21 is actuated to the position shown so that circulation of refrigerant is terminated and circulation of air in the chamber 12 initiated.

When the thermostat 79 calls for cooling, the condensing unit is started and, as the fan is operating, refrigeration of the circulating air in the chamber 12 is effected. As described heretofore, the rate of heat transfer is high at this time so that the major portion of the circulated refrigerant is vaporized in the evaporator 14. The refrigerant condensing unit is stopped when the thermostat 79 becomes satisfied but circulation of air in the chamber 12 is continued. During demands for cooling from both thermostats 21 and 79, the former controls, as the fan 25 is stopped by the open switch 37 at this time.

From the foregoing, it will be apparent that I have provided improved refrigerating apparatus having separately refrigerated compartments, wherein the compartments are selectively refrigerated, with provisions for refrigerating one compartment in preference to the other. Furthermore, my improved apparatus provides for forced circulation of air in a chamber during refrigeration thereof and for a period of time subsequent thereto. The invention provides for circulation of air in cycles during inactive periods of the refrigerant circulating means and for controlling circulation of air in accordance with the temperature of the evaporator cooling the air.

I have shown my improved apparatus having the low temperature element refrigerated in preference to the higher temperature element, when both require cooling, but it is to be understood that the higher temperature element may be given preference without departing from the spirit of my invention. Refrigerating machines other than the compression type shown may be employed as an element of my improved apparatus.

I have shown, for the sake of clearness, the various thermally responsive elements, per se, in their simplest form but it is to be understood that the preferred form of thermostats include quick acting mechanisms for the switches actuated thereby.

While I have shown my invention in several forms, it will be obvious to those skilled in the art that it is not so limited, but is susceptible of various other changes and modifications without

departing from the spirit thereof, and I desire, therefore, that only such limitations shall be placed thereupon as are imposed by the prior art or as are specifically set forth in the appended 5 claims.

What I claim is:

1. In refrigerating apparatus, the combination of means defining first and second cooling chambers, an evaporator element associated with each 10 of the chambers, means for circulating refrigerant through the evaporator elements, means responsive to the temperature in one of the chambers for controlling the refrigerant circulating means, means for translating air in heat 15 transfer relation with the evaporator element in the other chamber, and means responsive to the operation of said temperature responsive means and operative for rendering said air translating means ineffective during periods 20 when the temperature responsive means calls for cooling.

2. In refrigerating apparatus, the combination of means defining first and second cooling chambers, an evaporator element associated with each 25 of the chambers, means for circulating refrigerant through the evaporator elements, first and second means responsive to temperatures prevailing in the first and second chambers, respectively, for controlling the operation of the refrigerant circulating means, a fan for translating air in heat exchange relation with the evaporator element in one of the chambers, and means responsive to the operation of the temperature responsive means associated with the other of said chambers for rendering the fan 30 inactive during periods when the temperature-responsive means associated with the other chamber is calling for operation of the refrigerant circulating means.

3. In refrigerating apparatus, the combination of means defining first and second cooling chambers, an evaporator associated with each of the chambers, means for circulating refrigerant through the evaporators, means responsive 40 to predetermined high and low temperatures obtaining within the first chamber for starting and stopping the refrigerant circulating means, a fan for translating air within the second chamber in heat transfer relation with the evaporator therein, means responsive to predetermined high and 45 low temperatures obtaining within the second chamber for respectively initiating and terminating operation of the refrigerant circulating means, means for effecting operation of the fan during periods when said second chamber requires cooling and said first chamber is satisfied, and means responsive to the operation of the temperature responsive means associated with the first chamber for rendering said fan inactive 50 during periods when said first chamber requires cooling.

4. In refrigerating apparatus, the combination of a cabinet having a cooling compartment therein, an evaporator for cooling the air in the compartment, means for translating air within the compartment in heat transfer relation with the evaporator, means for circulating refrigerant through the evaporator, means responsive to a predetermined high temperature within the compartment for initiating operation of the refrigerant circulating means and for effecting operation of the air translating means, and means for intermittently effecting operation of the air translating means for predetermined periods of 60

time during periods when the refrigerant circulating means is inactive.

5. In refrigerating apparatus, the combination of means defining first and second cooling chambers, an evaporator element associated with each 5 of the chambers, means for circulating refrigerant through the evaporator elements, means responsive to predetermined high and low temperatures prevailing in the first chamber for initiating and terminating operation of the refrigerant circulating means, means responsive to a predetermined high temperature prevailing in the second chamber for initiating operation of the refrigerant circulating means and said fan, said last-mentioned means being effective in response to a predetermined low temperature obtaining in the second chamber for terminating operation of the refrigerant circulating means, and means for terminating operation of the fan subsequent to termination of operation of the 10 refrigerant circulating means by said second-mentioned temperature responsive means.

6. The combination as claimed in claim 5 having means operative during periods when the first-mentioned temperature responsive means 25 calls for operation of the refrigerant circulating means, for rendering the fan inactive irrespective of demands for its operation by the second-mentioned temperature-responsive means.

7. In refrigerating apparatus, the combination of means defining relatively high and low temperature cooling chambers, an evaporator element arranged within each chamber, a refrigerant compressor for supplying condensed refrigerant to the evaporator elements for vaporization therein, first and second thermostats responsive to temperatures prevailing in the low and high temperature chambers, respectively, said thermostats being effective in response to predetermined high and low temperatures for 30 respectively starting and stopping the compressor, a fan for circulating air within the high temperature chamber over the evaporator therein, means associated with the first thermostat for conditioning the fan for operation during periods 35 when the thermostat is satisfied and for rendering the fan incapable of operation when the thermostat is calling for cooling, means for operating the fan during periods when the second thermostat calls for cooling and when the fan is conditioned for operation, and means for periodically operating the fan during periods when both of 40 said thermostats are satisfied.

8. In a refrigerating system having first and second chambers to be refrigerated, first and second evaporators for cooling the air in said chambers, respectively, means for circulating refrigerant through the evaporators, a fan for translating the air within the second chamber in heat transferring relation with its associated 45 evaporator, means responsive to a predetermined temperature in the second chamber for initiating operation of the refrigerant circulating means, means effective when the temperature of the evaporator in the second chamber is below a predetermined value for effecting operation of the fan, means responsive to a predetermined temperature in the first chamber for initiating operation of the refrigerant circulating means, and means for rendering the fan inactive during 60 periods when the temperature responsive means in the first chamber is calling for cooling.

9. In a refrigerating system, the combination of means defining a chamber to be cooled, an evaporator disposed for cooling the air in the 65

- chamber, means for circulating refrigerant through the evaporator, a fan for translating air within the chamber in heat transfer relation with said evaporator, means responsive to a predetermined high temperature within the chamber for initiating operation of the refrigerant circulating means and the fan, said temperature responsive means being effective in response to a predetermined low temperature within the chamber for terminating operation of the refrigerant circulating means, and means for terminating operation of the fan after a predetermined period of time has elapsed subsequent to the termination of operation of the refrigerant circulating means by the temperature responsive means.
10. In a refrigerating system, the combination of means defining a chamber to be cooled, an evaporator disposed for cooling the air in the chamber, means for circulating refrigerant through the evaporator, a fan for translating air within the chamber in heat transfer relation with said evaporator, means responsive to predetermined high and low temperatures within the chamber for respectively initiating and terminating operation of the refrigerant circulating means, and means responsive to a predetermined high and low temperature of the evaporator for respectively terminating and initiating operation of the fan.
20. 11. In refrigerating apparatus, the combination of means defining first and second chambers, an evaporator structure having first and second portions disposed for cooling the air in the first and second chambers, respectively, means for circulating refrigerant through the evaporator, a fan for circulating air within one of the chambers in heat transfer relation with its associated evaporator portion, means responsive to predetermined high and low temperatures of the evaporator portion in the other chamber for starting and stopping operation of the refrigerant circulating means, means for rendering said fan inactive during periods when said temperature responsive means effects operation of the refrigerant circulating means and for conditioning the fan for operation during periods when operation of the refrigerant circulating means is stopped, and means responsive to the temperature of the second evaporator portion for controlling the operation of the fan during periods when it is conditioned for operation.
30. 12. In refrigerating apparatus, the combination of means defining first and second chambers, an evaporator structure having first and
- second portions disposed for cooling the air in the first and second chambers, respectively, means for circulating refrigerant through the evaporator portions, a fan for circulating air within one of the chambers in heat transfer relation with its associated evaporator portion, means responsive to a predetermined temperature of the air in said one chamber for conditioning said circulating means and said fan for operation, means responsive to a predetermined temperature of the evaporator portion in the second chamber for conditioning the circulating means for operation and for rendering the fan incapable of operation, and means responsive to the temperature of said first evaporator portion for controlling the operation of the fan during periods when both of said first-mentioned temperature responsive means are satisfied.
13. In refrigerating apparatus, the combination of means defining first and second cooling chambers, an evaporator associated with each of the chambers, means for circulating refrigerant through the evaporators, means responsive to predetermined high and low temperatures obtaining within the first chamber for starting and stopping the refrigerant circulating means, a fan for translating air within the second chamber in heat transfer relation with the evaporator therein, means responsive to predetermined high and low temperatures obtaining within the second chamber for respectively initiating and terminating operation of the refrigerant circulating means, and means for effecting operation of the fan at all times excepting periods when said first chamber requires cooling.
20. 14. In a refrigerating system, the combination of means defining a chamber to be cooled, an evaporator disposed for cooling the air in the chamber, means for circulating refrigerant through the evaporator, a fan for circulating air within the chamber in heat transfer relation with the evaporator, means responsive to a predetermined high temperature within the chamber for initiating operation of the refrigerant circulating means and the fan, said temperature responsive means being effective to terminate operation of the refrigerant circulating means in response to a predetermined low temperature within the chamber, and means for terminating operation of the fan in response to a predetermined temperature of the evaporator and after operation of the refrigerant circulating means has been terminated.
25. 30. 35. 40. 45. 50.

LESLIE B. M. BUCHANAN.
